(57) **CLAIM**

The ornamental design for a rangefinder, as shown and described.

DESCRIPTION

FIG. 1 is a front, left perspective view of a rangefinder, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear, right perspective view thereof; and,

FIG. 9 is a front, left perspective view thereof with the shading lines, which only help to show the shape and do not depict any surface decoration.

The broken lines in the drawings depict portions of the rangefinder that form no part of the claimed design.
